(57) **ABSTRACT**

A serial interface connector and corresponding method electrically connects to a storage cartridge that has a housing enclosing a serial communications device. The serial interface connector has a first plurality of electrical contacts and a retainer. The retainer operably contactingly engages the housing to impart a bias that retains the electrical contacts of the serial interface connector seated in electrical connection with a respective second plurality of electrical contacts of the serial communications device.

MODULAR INTERFACE COMMUNICATIONS WITH A STORAGE CARTRIDGE

RELATED APPLICATION

This application claims the priority of the earlier filing of application No. 61/347,152.

SUMMARY

In some embodiments a serial interface connector is provided having a flush-mount body portion and a protuberant sub-flush-mount reach portion extending longitudinally from the body portion. A plurality of electrical contacts is supported at a distal end of the reach portion. A retainer is supported by at least one of the body portion and the reach portion to operably impart a bias that retains the serial interface connector seated in electrical connection with another device.

In some embodiments a serial interface connector is configured to electrically connect to a storage cartridge that has a housing enclosing a serial communications device. The serial interface connector has a first plurality of electrical contacts and a retainer. The retainer operably contactingly engages the housing to impart a bias that retains the electrical contacts of the serial interface connector seated in electrical connection with a respective second plurality of electrical contacts of the serial communications device.

In some embodiments a method is provided that includes steps of obtaining a storage cartridge having a mass data storage device mounted inside a housing, the mounted mass data storage device having a serial data port that is recessed away from an inner surface of the housing by a predefined sway space distance; inserting a serial interface connector into the housing a distance more than the sway space distance to contactingly engage a distal end of the serial interface connector directly to the serial data port; and further inserting the serial interface connector to electrically seat the serial interface connector with the serial data port and to simultaneously engage a retainer portion of the serial interface connector with the housing to bias the seated serial interface connector and serial data port together.

BRIEF DESCRIPTION OF THE DRAWINGS

FIG. 1 is a cutaway isometric depiction of a serial interface connector constructed in accordance with embodiments of the present invention.

FIG. 2 is a top view of the serial interface connector of FIG. 1.

FIG. 3 is a side view of the serial interface connector of FIG. 2.

FIG. 4 is an enlarged portion of the serial interface connector of FIG. 2 depicting the protuberant actuator lobe of the retainer feature operably engaging the cartridge.

FIG. 5 is a cross sectional view of the serial interface connector of FIG. 2 depicting the crowder member operably engaging the cartridge.

FIG. 6 is an isometric depiction of a storage cartridge that is constructed in accordance with embodiments of the present invention.

FIG. 7 is an exploded isometric depiction of the storage cartridge of FIG. 6.

FIG. 8 is a cross sectional depiction of a portion of the storage cartridge of FIG. 6.

FIG. 9 is an isometric depiction of a communications interface that is constructed in accordance with embodiments of the present invention.

FIG. 10 is a view similar to FIG. 8 but with the interface connector seated with the drive's data port.

FIG. 11 is a top view similar to FIG. 2 but depicting the interface connector seated with the drive's data port.

FIG. 12 is a flowchart depicting steps in a method for MODULAR INTERFACE COMMUNICATIONS in accordance with embodiments of the present invention.

DETAILED DESCRIPTION

The demand for digital data storage capability now proliferates throughout many and diverse types of consumer electronics devices. Not only does the demand mean more devices have onboard storage capability, and not only is the demand consistently for more storage capacity in smaller packages, but more recently the demand is that the storage capacity 15 itself be modular, meaning it is portable and interconnectable. That is, for example, portable data storage devices are desired to store movies, audio, personal information, still pictures, maps or other navigation information, and the like, on the go. Making good practical use of the stored data requires that it 20 can be employed as a modular component, one that can be easily and reliably exchanged between various types of consumer electronics devices, such as desktop and laptop computers, digital media players, vehicle audio/video systems, distributed storage networks, and the like, employing various 25 different communications protocols.

Data storage devices like solid state drives, disc drives, and the like, advantageously offer high-capacity data storage capability with acceptably fast data transfer rates. Although such drives have successfully been employed as components 30 in portable devices, such as laptop computers and the like, such a drive is not well suited to be used as a portable device in and of itself. However, in accordance with the present 35 embodiments, such a drive can be well suited for such applications if it can be encased within a protective cartridge 40 housing and connected modularly to various different communications protocols.

FIGS. 1-3 are isometric, top, and side depictions, respectively, of a serial interface connector 100 forming a portion of a serial communications interface 102 (FIG. 9) that is constructed in accordance with embodiments of the present invention. The serial interface connector 100 has a body portion 104 (cutaway in FIG. 1) defining a substantially planar surface 106 extending between a top edge 108 and a bottom edge 110. The body portion 104 is sized and structured to 45 facilitate it being grippable, either manually or by an end effector, while operably connecting and disconnecting the serial interface connector 100 to/from a serial communications device. The serial interface connector 100 also has a protuberant reach portion 112 extending at a proximal end 50 55 114 thereof substantially orthogonally from the planar surface 106 and terminating at a cantilevered distal end 116. The reach portion 112 supports a plurality of electrical contacts 118 adjacent the distal end 116.

The serial interface connector 100 is sized and configured 60 to electrically connect to a storage cartridge (FIG. 6) that has a housing enclosing a recessed serial communications device. Advantageously, the serial interface connector 100 is configured to electrically connect directly to a data port of the serial 65 communications device itself, eliminating the need and associated cost of providing a flush mount connector for the recessed data port. Importantly, however, making an electrical connection with the recessed data port can be problematic

because the user or automated equipment inserting the serial interface connector 100 likely does not have line of sight access to the data port. Such an operation is referred to as a “blind connection,” because vision or optics cannot be relied upon to ensure that a robust electrical connection is made.

The serial interface connector 100 is configured with features that ensure that a desired robust connection is made consistently. First, the length of the reach portion 112 defines a reach insertion length 115 between its proximal and distal ends 114, 116 that is adequate for the electrical contacts 118 to reach and connect directly to the serial communication device’s data port, with no intervening electrical connector therebetween. Further, the serial interface connector 100 is provided with blind engagement features that align it with and retain it in connection with the serial communication device’s data port.

A first blind engagement feature is a retainer member 120. In these illustrative embodiments a pair of retainer members 120 is disposed on opposing edges of the reach portion 112, although the present embodiments are not so limited. The retainer member 120 here is a latch that is constructed of a spring clip affixed at proximal end 122 to the body 104 and cantilevered therefrom. A distal end of the spring clip is laterally constrained within a channel 124, and the spring clip is biased outwardly against an outer wall of the channel 124. These depicted embodiments are illustrative, not limiting, in that other embodiments contemplate the proximal end constrained in at least one of the body portion and the reach portion.

FIG. 4 depicts how, while inserting the serial interface connector 100, a protuberant actuator lobe 126 of the spring clip contactingly engages a respective deflector, such as a portion of a cartridge 128 into which the serial interface connector 100 is being inserted, to deflect the spring clip inwardly. The deflector can be a portion of the housing, a portion of the serial communications device in the housing, or a portion of some other component in the housing. The protuberant actuator lobe 126 clearly disengages the deflector when the serial interface connector 100 is fully inserted (FIG. 11), where it becomes seated with the serial communication device’s data port. That causes the spring clip bias to return it to the outwardly biased default position (as in FIG. 2). The spring clip’s return causes it to contactingly engage the outer wall of the channel 124 with sufficient energy to provide an audible and a tactile indication that the serial interface connector 100 is seated with the serial communication device’s data port. Thereafter, the resistance of the protuberant actuator lobe 126 to sliding in the opposite (disconnect) longitudinal direction past the deflector provides a retention force urging the serial interface connector 100 to remain electrically seated with the serial communication device’s data port.

Returning to FIG. 1, another blind engagement feature on the reach portion 112 is a longitudinally extending rail-shaped crowder member 130, generally forming a laterally protuberant member effectively increasing the thickness of the reach portion 112. In these illustrative embodiments a pair of parallel crowders 130 is depicted on the same planar side of the reach portion 112. In alternative equivalent embodiments only one crowder 130 can be used, or parallel crowders 130 can be provided with one or more on each of the opposing planar sides of the reach portion 112.

Each crowder 130 is advantageously provided with a tapered leading edge 131 to provide a smooth entry during insertion into the opening 154 (FIG. 6) defined by the cartridge 128. FIG. 5 depicts how each crowder 130 is sized (height in this depiction) to wedgingly provide an interference fit between the reach portion 112 and the cartridge 128

during insertion. The interference mating relationship advantageously removes any slack fit between the inserted reach portion 112 and the cartridge 128, resulting in a robust and positive engagement during insertion as well as an additional 5 retainer force that biases the connector 100 in the seated position.

Returning again to FIG. 1, another blind engagement feature on the reach portion 112 is a longitudinally extending and tapered protuberant member 134 that contactingly engages a 10 corresponding cavity in the cartridge 128 to operably align the reach portion’s distal end 116 with the serial communication device’s data port. Again, in these illustrative embodiments a pair of opposing protuberant members 134 is depicted although the contemplated embodiments are not so limited. Distal ends of the protuberant members 134 extend longitudinally beyond the reach portion’s distal end 116 so that during insertion the reach portion 112 is aligned to the serial communication device’s data port before the serial interface connector electrical contacts 118 contactingly 15 engage corresponding electrical contacts in the serial communications device’s data port.

The serial interface connector 100 can further be provided with a shield 136 constructed of a layer of electrically conductive material. The electrically conductive shield 136 20 advantageously provides a terminal to which elongated conductive fingers in the cartridge 128 can contactingly engage as the serial interface connector 100 is inserted. That conductive path allows for a controlled dissipation of any electrostatic charge from the cartridge 128, safeguarding the electrical components in the cartridge 128 and in the serial communications interface 102 (FIG. 9) from electrostatic discharge damage. The shield 136 also protects the electrical components in the cartridge 128 and in the serial communications interface 102 from electromagnetic interference.

FIGS. 6 and 7 depict assembled and exploded views, respectively, of the cartridge 128 in accordance with embodiments of the present invention. The cartridge 128 includes a pair of housing portions 140, 142 that are joined together to define an internal cavity 144. In the illustrative embodiments 30 of FIG. 7 the housing portions 140, 142 are connected together via a plurality of fasteners 146, although in alternative equivalent embodiments (not shown) they can be connected together otherwise such as by interlocking features and/or adhesive and the like.

45 The cartridge 128 includes a mass data storage drive 148 mounted within the housing 140, 142 in the cavity 144. The drive 148 can be a disc drive or a solid state drive, and the like. An elastomeric shock mount 150 can encompass the drive 148 in the cavity 144 in order to mechanically decouple the housing 140, 142 from the drive 148, thereby damping the environmental effects such as external shocks and vibration. Such drives 148 are typically commercially available in standard form factors, and internal locating features of the housing 140, 142 and/or the shock mount 150 can be provided to 50 selectively mount different form factor drives within the same size cartridge 128.

The drive 148 has a data port 152 configured for establishing 55 external communications with another device for executing access commands transferring data to and from a storage space in the drive 148. In the illustrative embodiments of FIG. 7 the drive 148 has a serial advanced technology attachment (SATA) port, although the claimed embodiments are not so limited.

The drive 148 is mounted such that the data port 152 is 60 operably recessed within the housing 140, 142, and the data port 152 is there aligned with an opening 154 defined by the housing 140, 142. FIG. 8 diagrammatically depicts the drive

148 and its data port 152 operably mounted in the housing 140, 142. The data port 152 has a leading edge 156 at an initial contacting engagement position of an external connector with the data port 152, and an upright abutment edge 158 providing a positive mating engagement reference surface at a final contacting engagement position where the external connector is seated with the data port 152. The distance between the leading edge 156 and the abutment edge 158 is referred to herein as the longitudinal seating distance 160 of the drive's data port 152. Traversing the data port 152 along the longitudinal seating distance 160 is a plurality of electrical contacts 162 that are exposed for electronically communicating with the external connector.

A longitudinal sway space distance 164 is provided between the leading edge 156 and an inner surface of the housing 140, 142, providing clearance that prevents the drive 148 from contacting the housing 140, 142 during normal operation. A longitudinal reach distance 166 for the external connector to seat with the drive's data port 152 is at least the sum of the longitudinal insertion distance 160, the longitudinal sway space distance 164, the thickness 168 of the housing 140, 142, and a desired longitudinal clearance distance 170 from the outer surface of the housing 140, 142 when the external connector is seated.

The reach portion 112 (FIG. 1) is cross sectionally sized to pass through the opening 154 (FIG. 1) in the housing 140, 142, making the serial interface connector 100 removably insertable into the cartridge 128. Importantly, the reach insertion length 115 (FIG. 1) extends longitudinally from the body portion 104 a distance that is at least the reach distance 166, operably spanning the predefined sway space longitudinal distance 164 when initially inserted so that the reach portion's distal end 116 contactingly engages the drive's data port 152 in the cartridge 128. From reduction to practice it has been determined that the reach insertion length 115 in preferred embodiments is at least nine millimeters long, or longer.

FIG. 9 is an isometric depiction of a serial communications interface 102 that is constructed in accordance with embodiments of the present invention. The serial communications interface 102 includes a communications cable 172 configured to join a remote device (not shown) outside the housing 140, 142 to the serial interface connector 100. In these illustrative embodiments the serial communications interface 102 has another interface connector 174 that is removably connectable, such as being slidably connectable, to the remote device (not shown).

FIG. 10 diagrammatically depicts the serial interface connector 100 seated with the data port 152 of the cartridge 128 for operational communications with the drive 148. The body portion 104 is flush-mounted to the housing 140, 142, meaning that when seated the body 104 remains entirely outside the housing 140, 142 and in close proximity thereto separated only by the desired clearance 170. The reach portion 112, contrarily, is sub-flush-mounted to the housing 140, 142, meaning that when seated it passes through the opening 154 (FIG. 8) and extends into the cavity 144 (FIG. 7). Importantly, the sub-flush-mounted reach portion 112 defines a reach insertion length 115 that is sufficient to directly connect to the data port 152 (FIG. 7) without any other intervening electrical connector therebetween. Upon making the initial contacting engagement, the electrical contacts 118 at the reach portion's distal end 116 slidingly engage the contacts 162 in the drive's data port 152. The electrical contacts 118 in some interfaces are electrically connected to a printed circuit board (PCB) 176 contained within the body portion 104 of the interface connector 100. Communications bridge circuitry 178 can reside on the PCB 176, translating access commands for use

in the interface communications protocols of the drive 148 and of the remote device. For example, in the illustrative embodiments the serial communications interface 102 can include a communications bridge circuitry 178 bridging the SATA communications protocol of the drive 148 to the communications protocol of the remote device (not shown).

FIG. 11 depicts a top view of the serial interface connector 100 seated with the data port 152 as previously discussed in relation to FIG. 10. This view best depicts how the tapered protuberant members 134 first insertingly engage the cartridge 128 (in this case the drive 148) to align the connector 100 with the data port 152. Note that in this seated insertion position, the protuberant actuator lobes 126 have clearly disengaged the cartridge 128 (such as housing 140, 142) and are thereby free to spring outwardly to impart a retainer bias urging the interface connector 100 and the data port 152 together.

The present embodiments contemplate a method corresponding to the aforescribed apparatus. FIG. 12 is a flowchart depicting steps in a method 200 for MODULAR INTERFACE COMMUNICATIONS in accordance with embodiments of the present invention. The method 200 begins in block 202 with obtaining a cartridge having a mass data storage device with a data port that is recessed by a predetermined sway space distance within a protective housing. In block 204 the connector is inserted into the cartridge a distance at least more than the sway space distance to contactingly engage a distal end of the interface connector directly to the data port. After that initial contact, in block 206 the connector is inserted further to electrically seat the interface connector with the data port and to simultaneously engage the retainer member portion of the interface connector with the cartridge to bias the seated interface connector and the data port together.

It is to be understood that even though numerous characteristics and advantages of various aspects have been set forth in the foregoing description, together with details of the structure and function, this disclosure is illustrative only, and changes may be made in detail, especially in matters of structure and arrangement to the full extent indicated by the broad general meaning of the terms in which the appended claims are expressed.

What is claimed:

1. A serial interface connector comprising:
a flush-mount body portion;
a protuberant sub-flush-mount reach portion extending longitudinally from the body portion to a distal end at a first distance;
an alignment member extending longitudinally from the body portion a second distance that is greater than the first distance for alignment of the serial interface connector with another device;
a plurality of electrical contacts supported at the distal end of the reach portion; and
a retainer supported by at least one of the body portion and the reach portion operably imparting a bias that retains the serial interface connector seated in electrical connection with another device.

2. The serial interface connector of claim 1 wherein the reach portion defines a longitudinal reach insertion length of at least nine millimeters from the body portion to the reach portion distal end.

3. The serial interface connector of claim 1 comprising an electrically conductive shield supported by at least one of the body portion and the reach portion.

4. The serial interface connector of claim 1 wherein the retainer comprises a spring clip.

5. The serial interface connector of claim 4 wherein the retainer comprises two opposing spring clips.

6. The serial interface connector of claim 4 wherein the spring clip is affixed at a proximal end to at least one of the body portion and the reach portion and is longitudinally cantilevered from the proximal end.

7. The serial interface connector of claim 6 wherein a distal end of the spring clip is laterally constrained within a channel supported by at least one of the body portion and the reach portion.

8. The serial interface connector of claim 7 wherein the spring clip comprises a laterally protuberant actuator lobe medially disposed between the proximal and distal ends.

9. The serial interface connector of claim 1 comprising a 15 crowder member sized to operably provide an interference mating relationship removing slack fit between the interface connector and the another device.

10. The serial interface connector of claim 9 wherein the crowder member comprises a protuberant member extending laterally from the reach portion.

11. The serial interface connector of claim 10 wherein the crowder member extends longitudinally along the reach portion.

12. The serial interface connector of claim 11 comprising 25 two crowders on one side of the reach portion.

13. The serial interface connector of claim 11 comprising a crowder on each of opposing sides of the reach portion.

14. The serial interface connector of claim 1 comprising a 30 serial advanced technology attachment (SATA) configuration.

15. The serial interface connector of claim 1 wherein the another device is selectable from the group consisting of a disc drive and a solid state drive.

16. A serial interface connector configured to electrically 35 connect to a storage cartridge that has a housing enclosing a serial communications device at a predetermined sway space distance within the housing; an alignment member extending longitudinally from the serial interface connector for alignment of the serial interface connector with the serial communication device, the serial interface connector comprising a first plurality of electrical contacts and a retainer, the retainer operably contactingly engaging the housing to impart a bias 40 that retains the electrical contacts of the serial interface con-

necter seated in direct contacting engagement with a respective second plurality of electrical contacts of the serial communications device.

17. The serial interface connector of claim 16 comprising a body portion and a sub-flush-mount protuberant reach portion supporting the first plurality of electrical contacts, the sub-flush-mount reach portion extending longitudinally from the body portion to define a longitudinal reach insertion length from the body portion to a distal end of the reach portion that is greater than the distance that the serial communication device is recessed inside the housing.

18. The serial interface connector of claim 17 wherein the retainer comprises a spring clip affixed at a proximal end to at least one of the body portion and the sub-flush-mount protuberant reach portion and is longitudinally cantilevered from the proximal end, a distal end of the spring clip being laterally constrained within a channel supported by at least one of the body portion and the sub-flush-mount protuberant reach portion, and an actuator lobe medially disposed between the proximal and distal ends.

19. The serial interface connector of claim 16 comprising a 20 crowder member sized to operably provide an interference mating relationship removing slack fit between the interface connector and the housing.

20. A method comprising:
obtaining a storage cartridge having a data storage device mounted inside a housing, the mounted data storage device having a serial data port that is recessed away from an inner surface of the housing by a predefined sway space distance;
inserting a serial interface connector into the storage cartridge housing a distance more than the sway space distance to contactingly engage a distal end of the serial interface connector directly to the data storage device inside the housing; and
further inserting the serial interface connector to electrically seat a first plurality of electrical contacts of the serial interface connector in direct contact with a second plurality of electrical contacts of the data storage device and to simultaneously engage a retainer portion of the serial interface connector in direct contact with the housing to bias the first and second sets of electrical contacts together in the direct contacting engagement.
